UNITED STATES PATENT OFFICE.

GEORGE A. LABOURN, OF SIOUX CITY, IOWA.

BREEDING-CRATE.

No. 864,006.

Specification of Letters Patent.

Patented Aug. 20, 1907.

Application filed December 1, 1906. Serial No. 345,948.

To all whom it may concern:

Be it known that I, GEORGE A. LABOURN, a citizen of the United States of America, residing at Sioux City, in the county of Woodbury and State of Iowa, have 5 invented new and useful Improvements in Breeding-Crates, of which the following is a specification.

This invention relates to breeding crates for hogs, and one of the principal objects of the same is to provide simple and efficient means for adjusting the various parts quickly and by means of a single lever.

Another object of the invention is to provide a crate of simple construction which will be safe, economical and efficient in use, and which can be produced at comparatively slight cost.

15 These and other objects may be attained by means of the construction illustrated in the accompanying drawings, in which:

Figure 1 is a side elevation of a breeding crate made in accordance with my invention. Fig. 2 is a longitudinal section of the same. Fig. 3 is a front elevation. Fig. 4 is a detail plan view of a double crank lever for adjusting the foot rests.

Referring to the drawings for a more particular description of my invention, the numeral 1 designates the 25 longitudinal bars of the crate, and 2 are the upright bars at the rear end of the crate. The longitudinal bars 1 are provided with a diagonal brace 3 which extends from the bottom of the rear portion to the inclined front bars 4. The floor 5 is supported on sills 6. A 30 door 7 is hinged to the front portion of the crate upon a crank rod 8 provided with a lever 9 at one side of the crate for holding the door 7 in an inclined position when open, said lever 9 being adjustable by means of perforations 10 and a removable pin 11 in order that the 35 door may be raised or lowered at its hinged end so that when the foot boards 15 are adjusted downwardly, the front ends of said boards will lie in the same plane as the rear or hinged end of the door 7 so that the animal will walk from the door 7 upon the foot rests 15. A lid 40 or cover 12 is hinged at 13 to a cross board 14 at the top of the crate. Pivoted upon the uprights 2 at the rear end of the crate are foot rests 15. Near the front ends of the foot rests and underneath the same are connected

links 16 and at the lower ends of said links the same are connected to a double crank lever 17, the crank portions 18 of which extend at right angles to the main portion of the lever. The ends of said lever 17 are pivoted in the bottom side boards 19, and the end of said lever 17 is squared, as at 20, to accommodate an operating handle 21 fitted to the squared end. A series of perforations 22 are formed in the board 19 and a suitable pin is fitted in said perforation to hold the operating handle 21 in adjusted position. The central portion of the crank lever 17 extends under a central longitudinal spreader board 23, pivoted at 24 to the rear uprights 50 2. The spreader board 23 near its front end is provided with a keeper *a*, and passing through said keeper is the crank portion *b* of a crank lever *c* pivoted at its ends in the longitudinal bars 19 of the crate. When it is required to adjust the spreader board 23, the arms *d* of 60 the lever *c* are grasped and moved toward the front or rear of the crate.

From the foregoing it will be obvious that a device constructed in accordance with my invention is simple in construction, can be quickly adjusted by means of 65 the levers 21, 9 and *c*, and that the device is strong, durable and efficient for its purpose.

Having thus described the invention, what I claim is:

1. In a breeding crate, a door hinged to the front end of 70 the crate provided with a lever for adjusting said door vertically at its inner end, a pair of foot rests pivotally connected to the rear end of the crate, a crank lever pivoted at its ends to the crate and connected by links to said foot rests, a spreader board, and a crank lever connected 75 to said spreader board.

2. In a breeding crate, a pair of foot rests, a double crank lever, links connecting said lever to said foot boards, a spreader board, a lever for adjusting said spreader board, a crank lever, and a door connected to said crank 80 lever for raising the hinged end of said door relatively to the foot rests, substantially as described.

In testimony whereof, I affix my signature in presence of two witnesses.

GEORGE A. LABOURN.

Witnesses:

LIZZIE M. HUBBNER,
JOHN F. JOSEPH.
